(57) CLAIM

We claim the ornamental design for a dispensing plate for shower head, as shown and described.

DESCRIPTION

FIG. 1 is a perspective view of a dispensing plate for the present invention, showing the dispensing plate in the environment of a hand-held shower head (which shower head, in broken lines, forms no part of the invention);

FIG. 2 is a perspective view of the dispensing plate of FIG. 1, but shown in the environment of a wall-mounted shower head (which shower head, in broken lines, forms no part of the invention);

FIG. 3 is a perspective view of the obverse side of the dispensing plate of FIG. 1;

FIG. 4 is a left side view of the dispensing plate of FIG. 3;

FIG. 5 is a frontal view of the obverse side of the dispensing plate of FIG. 3;

FIG. 6 is a bottom side view of the dispensing plate of FIG. 3;

FIG. 7 is a top side view of the dispensing plate of FIG. 3; and,

FIG. 8 is a view of the reverse side of the dispensing plate of FIG. 3.

Features shown in broken lines in the drawings are not part of the claim.
